UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

METHOD OF AND MACHINE FOR MAKING KNOCKDOWN BOXES.

Application filed February 5, 1921. Serial No. 442,868.

To all whom it may concern:

Be it known that we, LEON E. LA BOMBARD and MELVIN H. SIDEBOOTHAM, citizens of the United States, and residents of Chelsea, in the county of Suffolk and State of Massachusetts, have invented certain new and useful Improvements in Methods of and Machines for Making Knockdown Boxes, of which the following is a specification.

This invention relates to the manufacture of boxes of the type commonly known as "knock down" or wall boxes which are furnished to the trade in flat or collapsed condition for the purpose of saving space in stock rooms and in stores where they are to be used, and also for saving transportation costs. Such boxes are opened or "set up" as they are needed for use, and when set up 20 have upright walls. Boxes of this type are used very largely for packaging eggs sold at retail (some well-known form of cross partitioning being employed in the boxes), but it is to be understood that we do not limit 25 ourselves to the manufacture of boxes for such specific use.

Knock-down wall boxes are more difficult to make than what are known as carton boxes because the latter are made by folding 30 blanks on two parallel crease lines, the complete boxes simply consisting of tubes having end tucking flaps. And envelopes are made by simply first folding the blanks on two parallel lines and then on two other 35 parallel lines. On the other hand boxes of the type illustrated by Figures 14 to 20 herein have wall portions that must stand upright from the bottom when the boxes are to be used. To manufacture such 40 boxes in collapsed or "knocked down" condition (Fig. 19) necessitates folding the wall portions of the boxes onto the bottom section, which wall portions will then, when set up (Fig. 20) be so connected to each other as 45 to present a continuous barrier to prevent escape of the contents of the box. The chief difficulty in manufacturing such boxes by automatic machinery has heretofore been in providing mechanism which will properly 50 fold the sections of the blanks which are to constitute the foldable side walls of the boxes. Machines have been made which will do part of the work of producing such wall boxes, such mechanism being of a

plunger type and consequently intermittent 55 in action and therefore relatively slow in operation, and requiring some hand operation to aid in the production of the boxes for the market. So far as we are aware, we are the first to provide a machine which is automatic and continuous in the operation of 60 converting flat blanks into collapsed boxes which have wall portions adapted to be straightened to upright positions.

The present invention includes a novel 65 method of producing "knock-down" boxes, whereby we effect economy in the material employed and a very material increase in speed of production, the latter being particularly true when the method is carried 70 out by machinery. The invention also includes a novel machine for producing boxes rapidly according to the said method.

The features of novelty embraced in our invention will be explained hereinafter and 75 pointed out in the claims.

Of the accompanying drawings:

Figures 1 and 2 are, respectively, plan views of the first and second sections of our improved machine omitting blank feeding 80 and box stacking mechanisms and also omitting some of the details to avoid confusion.

Figure 3 is a perspective view of that portion of the first section where the side wall 85 portions of the blanks are folded.

Figure 4 is a perspective view of some of the details belonging to the mechanism of Figure 3 but only partly appearing in that figure.

Figures 5, 6, 8, 9 and 10 are perspective 90 views illustrating successive steps in the operation of folding the side wall portions of the blanks.

Figure 7 is a detailed perspective looking in a direction the reverse of that in 95 Figure 3.

Figure 11 is a perspective view of the mechanism at the junction of the first and second sections of the machine.

Figures 12 and 13 are perspective views 100 illustrating the operation of the gluing mechanism which is located in the second section of the machine.

Figures 14 to 19 inclusive are views 105 illustrating successive steps in the folding of the blanks.

Figure 20 is a perspective view of a box which has been converted from the col-

lapsed condition shown in Figure 19 to a set up condition ready to be filled.

In many of the figures arrows indicate the direction in which the blanks travel 5 while passing through the machine.

Referring first to Figures 1 and 2, it will aid toward an understanding of the following description to explain that those two figures, taken together, indicate the 10 entire machine excepting that in practice there is a suitable blank feeding mechanism at the right of Figure 1 and a box stacking or collecting mechanism at the left of Figure 2. The left hand end of Figure 15 duplicates parts shown at the right hand end of Figure 2 to render it clear that the parts of the machine shown in the two figures operate at an angle to each other. In said Figures 1 and 2 some of the positions and outlines of the blanks are indicated by dotted lines where the dotted numerals 15, 17, 18 and 19 appear. Those dotted numerals are employed because at those points of the machine the blanks are 20 substantially the conditions shown by Figures 15, 17, 18 and 19. In other words, each blank when it reaches position 15 (Fig. 1) is as shown in Figure 15; when it reaches position 17 it is substantially as shown by Figure 17; and so on until, when it reaches position 19 (Fig. 2), it is substantially as shown by Figure 19. The timing is such that when the machine is in operation different parts of the machine are operating 30 simultaneously on blanks which are passing along successively and continuously spaced about as indicated by the dotted line indications of the blank in Figures 1 and 2. In other words, while one part of the 40 machine is performing a partial folding operation on one blank other parts of the machine are at the same time performing other folding operations on other blanks, all of said blanks following one another in a continuous line or stream through the machine 45 and delivered therefrom as complete boxes in collapsed condition (Fig. 19).

The frame of the machine includes side bars 20 supported by suitable legs a portion 50 of one leg being indicated in Figure 3 at 21. The side bars are connected by tie rods one or two of which are indicated at 22 and others by other numerals herein-after referred to. The frame also includes 55 brackets rising from the side bars at points where desirable for some of the parts of the machine. Two of such brackets are indicated at 23 in Figures 1 and 3.

Blanks shaped as indicated in Figure 14 60 are cut and creased to form a bottom portion *a*, front and rear wall sections *b* *c*, side wall sections *d* *e* *f*, flaps *g* at the ends of section *b*, flaps *h* at the ends of section *c*, a cover section *i* and a tucking flap *k*. Blanks of this shape are cut with practi-

cally no waste of material as will be understood by visualizing a second blank placed against the one in Figure 14 edge to edge but in reversed longitudinal position. The edges of the parts *d* *e* *f* *g* of one blank will just meet and correspond with the edge 70 of parts *i* *k* of the adjacent blank and the flap *h* of the first blank will just fit the space between the parts *f* *h* of said adjacent blank. In other words the edges are 75 reversely complementary.

Blanks of the shape just described are taken singly and successively from a feed table (not shown) by a feed wheel 24 (Figs. 1 and 3) carried by shaft 25, and are then 80 taken by a pair of rolls 26, 27, which forward them onto two smooth stationary strips 29 supported by two of the tie rods. The shaft of roll 26 is indicated at 28. These upper and lower rolls 26, 27, are employed because they act more positively than 85 would the wheel 24 alone to secure proper timing or relative spacing of the succession of blanks and the delivery thereof onto the strips 29.

The strips 29 are adjustably mounted on their supporting tie rods to provide for different widths of blanks, and they are formed or provided with outer raised guides 30 for the edges of the blanks. Said guides however are omitted along those portions where the marginal wall portions of the blank are turned or folded in as described presently in connection with Figures 5, 6, 8 and 9.

Mounted on tie rods of the machine are 100 two channeled guide bars 31 for driven chains 32 (Figs. 3 and 10) having hook-shaped lugs 33, (Fig. 10). The lugs of each chain are spaced so far apart that after a blank has been delivered onto the strips 105 29 by the rolls 26, 27, its rear edge (the edge of section *b*) is not at once engaged by a pair of lugs 33 but only after said blank has remained stationary long enough in position 15 (Fig. 1) for the mechanism shown 110 in Figures 3, 5 and 6 to act to fold the marginal portions of the blank to substantially the form shown by Figure 16. The blank stops in said position simply because as soon as its rear edge leaves the nip of the forwarding rolls 26, 27, there is nothing to carry it further until a pair of the chain lugs 33 reach it. And the blank is of so little weight that it is caused to stop by friction. Said friction is effected by the 115 stationary strips 29 and a pair of upper guide strips 34 having inclined ends 35 (Fig. 7) to permit the blanks to enter between the upper and lower strips as they are supplied to the machine from the feeder. The upper strips 34 are suitably supported by hangers 36 from blocks 37 adjustably mounted on a tie rod 83.

Each blank, advanced in the direction of

the arrow in Figure 14, arrives at and stops in the position shown in Figure 5 which figure, to avoid confusion, omits many of the operating parts shown in Figure 3. 5 While the blank is being forwarded by the rolls 26, 27, to the position shown in Figure 5 its marginal portions *d e f g h* are "broken" on the longitudinal crease lines and turned to upright positions (Fig. 15) 10 by a pair of rods 38 (Fig. 1) of a type well known in box making machines. The resistance offered by the breaker rods 38 to the forward movement of the blank is reliably overcome by the positive action of 15 driven rolls 26, 27. The timing of operation of the various parts of the machine is such that nothing acts to move the blank from the position shown in Figure 5 until after its marginal portions *d e f* have been turned 20 in or folded and doubled to the conditions approximately illustrated in Figure 10. We will now describe the mechanism which operates to turn or fold the said portions *d e f* of the blank while it is stationary, from 25 the up-standing form shown in Figures 5 and 15, through the forms shown in Figures 6, 8, 9 and 16, to that shown in Figure 17.

When the blank arrives in the position shown in Figure 5, its marginal portions are 30 held upright by side rods 39, 40, which project in parallel relationship from blocks 41, 42, (Figs. 1, 3 and 5) secured to the outer edges of the strips 29.

To engage the upright wall portions *d d* 35 of the blank and bend them toward each other on their crease lines, tuckers 43 are employed. Said tuckers are located at opposite sides of the path of movement of the blanks. That is, they are outside said path 40 of movement, and they act on the outer sides or surfaces of the upright marginal portions of the blank while the latter is in its position of rest. Said tuckers are hereinafter referred to generically as outside 45 folders to aid in distinguishing them from the wing folders 72, 73, 74, 75 hereinafter described and which are so located as to act as inside folders. Said outside folders or 50 tuckers 43 move from the position shown in Figure 5 to that shown in Figure 6. Each of them, for convenience of structure, consists of a pair of plates secured to a rock shaft, but the two plates may be integral. The inner or acting margin of each side 55 tucker 43, whether said tucker consists of one plate or two plates, presents an angular edge the tip of which is at the center. Each rock shaft is mounted in bearings provided in a bracket 45 (Figs. 3, 5 and 6). The two brackets are mounted to slide toward and from each other on a tie rod 22. Each bracket is rigidly connected to a rod 46 mounted to slide (Fig. 4) in frame bracket 23 and in a bearing bracket 47 rigidly supported by said tie rod 22.

The two rock shaft brackets 45 are caused to simultaneously slide toward and from each other to cause the tuckers or outside folders 43 to bend the portions *d e f* in and down, by the following mechanism:—A 70 cam 48 (Fig. 4) secured to the feed wheel shaft 25 acts on a roll 49 of an arm 50 of an elbow lever pivotally supported by frame bracket 23. Another arm 51 of said lever is connected by a link 52 with an arm 53 of an elbow lever pivotally supported at 54 and having another arm 55 connected to a block 56 secured to the outer end of one of the slide rods 46. Each slide rod 46 has a block 57 secured to it, and the two blocks 57 are 80 connected by links 58 with opposite ends of a lever 59 pivoted at its mid-length to the under side of a block 60 clamped on tie rod 22. The cam 48 acts to slide the rods 46 and the brackets 45 in, while a spring 61 connected to one of the links 58 acts to slide the rods and brackets out. 85

When the members 43 are in their outer positions (Figs. 3 and 5) they are held tilted upward by springs connected to arms 90 62 of the two rock shafts so that the angular tips of the said members (when moved in) will engage the portions *d* of the blanks well above the line where they join the flat body portion *a* of the blank. This is to 95 avoid liability of said tips puncturing the upright portions *d*. When the slide rods 46 move in, the tuckers swing down to press the portions of the blank engaged thereby down flat (Fig. 6). This is effected by a 100 tail piece 63 clamped to each rock shaft and having its outer end inclined or curved down over a block 64 clamped on tie rod 22 so that, as the brackets 45 move in, the tail pieces 63 of the rock shafts ride over the 105 blocks 64 and effect rocking of the shafts to swing the tuckers or outside folders down positively.

Each rock shaft has a pair of arms or fingers 65 adjustably clamped thereto. Some 110 box blanks are of such material that they do not "break" easily on their crease lines. The fingers 65 are for the purpose of ensuring breaking of the flaps *g h* on their crease lines. To do this the fingers are so adjusted on the shafts 44 that when the tuckers move in, the tips of the fingers 65 engage the flaps *g h* near the lower portions thereof and bend them sharply inwardly. When they move out again the said flaps simply 115 spring back lightly to the limit prescribed by the rods 38, 39, 40.

After the outside folders or tuckers 43 reach their inner positions (Fig. 6) they remain there long enough to retain the portions *d* folded in and flat down (Fig. 16) 125 while other members presently described fold or double the triangular portions *e f* of the blanks over the tapering edges of the members 43. Said other members comprise 130

wing folders which oscillate on a vertical axis. The support therefore comprises a bearing block 66 (Figs. 5, 6, 8 and 9) rigid with a block 67 clamped on a tie rod 68 (Fig. 3) which connects the frame brackets 23.

Mounted to oscillate, and reciprocate slightly, in the bearing block 66 is a tubular shaft 69 within which is an inner shaft 70. Riveted to the lower end of the outer shaft 69 is a strip 71 rigidly carrying a front wing folder 72 and a rear wing folder 73. The terms "front" and "rear" are employed merely to distinguish which folders normally extend toward the foremost end and the rearmost end of the blank (see arrow in Figure 5). Riveted to the lower end of the inner vertical shaft 70 are a front wing folder 74 and a rear wing folder 75. The four wing folders are substantially flat and are of angular form substantially as illustrated so that when the front folders are swung apart and the rear folders are simultaneously swung apart by mechanism such as presently described, the outer edges of the four folders will act upon the inner sides or surfaces of the sections *e f* of the blank to double or fold them on their crease lines back onto the outside folders or tuckers 43, as shown by comparing Figures 8 and 9. Figure 16 illustrates the blank with its sections *e f* at an intermediate point of the operation just described. The timing is such that the members 43 are withdrawn and move outward just after the wing folders have operated as described, but said wing folders then hold the portions *d e f* in their in-folded positions to guide them under the flat spring fingers 99 (Fig. 10) when the blank is later pushed along by the chain lugs 33. The wide flat form of the wing folders provides for this guiding function.

The reason for providing mechanism for imparting vertical movements to the shafts 69, 70, is to cause the wing folders, when they swing apart, to be in a plane sufficiently elevated to cause their outer edges to engage the sections *e f* well above the crease lines, to bend or fold said sections over without risk of tearing them. Then the folders descend to press said sections down flat and hold or guide them while being passed along as the blank is pushed or advanced by the chain lug. To effect the vertical movements of the shafts 69, 70, an elbow lever 76, 77, (Fig. 5) is pivoted at 78 to one side of the fixed block 67, the arm 76 having a pin or roll 79 engaging an annularly grooved collar 80 fixedly carried by the tubular shaft 69 above block 66. Pivoted to the arm 77 of said elbow lever is one end of a rod 81 which is guided in a small block 82 (Figs. 1 and 7) mounted on a tie rod 83, the other end of said rod 81 being acted upon by a cam

84 carried by the shaft 25. A spring 85 connecting the arm 77 with the fixed block 82 coacts with the cam 84 in effecting the vertical movements of the tubular shaft 69 and the shaft 70 mounted therein in proper timing to raise and lower the wing folders as described.

To oscillate the inner and outer vertical shafts to simultaneously swing apart the front pair and rear pair of wing folders, the following mechanism is provided:—The upper end of the outer shaft 69 has a laterally extending arm 86 (Fig. 5) and the upper end of the inner shaft has a laterally extending arm 87. These two arms are connected, by adjustable links 88, with two arms 89 of a rock shaft 90 (Figs. 1 and 3) mounted in the frame brackets 23. An arm 91 of said rock shaft is connected by a link 92 with the upper end of a strut 93 pivoted at 94 to the frame bracket. A roll 95 at the junction of the link and strut is acted upon by a cam 96 carried by shaft 25, a suitably connected spring 97 coacting with the cam to rock the shaft 90 and oscillate the vertical shafts and swing the wing folders as hereinbefore described.

The rear edges of the two rear wing folders 73, 75, have upwardly bent portions 98 (Figs. 5 and 6) to render it certain that the lugs of the chains which pass close under said folders will not catch upon said folders and cause damage.

The timing of the operation of the parts of the machine shown in detail in Figures 3 to 9 inclusive is such that the side folders or tuckers 43 first move in from the position shown in Figures 3 and 5 and then down as shown in Figure 6. The blank is then in the condition shown in Figure 16 except that its portions *e f* are not yet turned up as shown in that figure but are flat as in Figure 6. Then the wing folders swing apart (Fig. 8) and turn up the sections *e f* (Fig. 16) and continue to swing apart and also move down (Fig. 9). This completes the folding of the portions *d e f*, and just after this a pair of lugs 33 of the chains "catch up" with the rear edge of the blank and begin to push it along. The portions *g h* of the blanks are still standing substantially upright, and as the blank moves along, the in-folded portions *d e f* slide out from under the wing folders which then return to the normal position of Figure 3. The side folders or tuckers slide out to normal position just before the blank begins to be moved along by the chain lugs, and therefore said tuckers present no obstacle to the passage of the sections *d e* along under the wing folders. Said wing folders remain in their outer positions shown in Figure 9 long enough to permit the wide outer portions of the front folders 72, 74, to act as guides to direct the in-folded

portions of the blank under a pair of spring fingers 99 (Figs. 5, 6, 8, 9 and 10) extending above the strips 34 over which latter the portions *d e f* have been folded. Each finger 99 is carried by a rotatively adjustable disk 100 (Fig. 5) supported by an arm 101 fixedly depending from a block 102 fixed on tie rod 68 (Figs. 1 and 3).

As best illustrated by Figure 10 the fingers 99 serve to prevent un-folding of the portions *d e f* while the blanks move along for the folding in of the flaps *h g* as presently described.

As the blank is pushed along by the chain lugs (Fig. 10) its flaps *h g* ride along the inner sides of a pair of folder rods 103 (Figs. 1, 3 and 10) extending from blocks 104 supported by the strips 29. Said rods are so formed longitudinally that they serve to fold the flaps *h g* in, and they are long enough to guide and hold said flaps as well as the portions *d e f* turned in as in Figure 17 until the folded flaps are in alinement with the previously folded portions *d e f* and reach the nip of a pair of press rolls 106, 107 presently described.

Sometimes it is desirable to employ a pair of supplemental flap-guiding rods 105 (Fig. 10) the tips of which extend to a point where they will bear on the flaps quite near the crease lines thereof to effect the flattening down of said flaps.

Each blank in the condition shown in Figure 17 is pushed along until its front portion *k* reaches the nip of two rolls 106, 107 (Figs. 1 and 11) which serve two purposes. First they pull the blank away from the hooked lugs of the chains so that said lugs will not damage the rear edges of the blanks when the lugs pass down around the sprockets carried by shaft 108 (Fig. 1), and they so press the portions *d e f g h* as to complete the folding thereof. The first of these functions is due to the fact that the rolls are driven at a peripheral speed exceeding the speed of travel of the chains 32. This increase of speed also effects a widening of the space between each blank and the one following it so that the said following one will not overlap the preceding one and interfere with its lateral movement after passing the rolls. The means for effecting such lateral movement will be presently described.

The lower roll 107 (Fig. 11) is larger than the upper roll 106 and is carried by a shaft 109 mounted in frame bearings. The shaft of the upper roll 106 is mounted in bearings at the ends of arms 110 pivotally supported by a tie rod 22 so that said roll bears yielding on the roll 107 or on blanks passing between the rolls.

Each blank reaching and passing the rolls 106, 107, is completely folded on its longitudinal crease lines and it then passes to and

through another part of the machine which folds it on its transverse crease lines. Referring first to Figure 11 in connection with Figure 1, the blank in the condition shown in Figure 17 passes from the rolls onto a table consisting of a plurality of plates 111 spaced for the passage between them of chains 112 having hooked lugs 113. Said table plates are supported by suitable means such as a bar 114 a portion of which is shown in Figure 1.

Mounted so it can be swung upwardly on a rod 115 supported by a frame bracket 116, is a frame consisting of two bars 117 connected as by a strip 118 and adapted to be held in the position shown in Figure 11 by suitable means such as a latch device indicated at 119. As soon as the rear edge of a blank passes the nip of the rolls 106, 107, it stops in the position shown in Figure 11 because of the friction between it and the table plates 111 and the bars 117. As a matter of fact therefore, the rolls 106, 107, determine the position of momentary rest of the partially folded blanks, and no arresting stops are necessary although such stops might be employed without departing from our invention.

The frame bars 117 may be lifted when it is desired to obtain access to anything below them.

Referring now to Figures 12 and 13 in connection with Figures 1 and 10, the blanks having their side marginal portions *d e f g h* folded as described, are successively pushed along over strips 120 which, as a matter of convenience of structure, may be extensions of the plates 111. Said blanks pass under strips 121 toward the glue applying mechanism which is carried by the second section of the machine, said second section being shown in Figure 2. Conveniently the strips 121 extend from and are supported by the bars 117.

Each blank travels in the direction of its length while in the first section of the machine, and then travels laterally or in the direction of its width while passing through the second section. The first operation in the second section is to apply a suitable adhesive, hereinafter referred to as glue, to the upper surfaces of the four triangular portions *e f* of each blank. Said glue is applied by four rotary pads which, as best shown in Figures 12 and 13, are arranged as two pairs, one pair 122 applying glue to the portions *e f* which are at the front as the blank travels in the direction of the arrow, and the other pair, 123, applying glue to the portions *e f* at the rear. The pads are triangular in face view to correspond with the shape of the portions *e f* and are curved to a radius the same as that of the circular path which they follow. They are carried by arms 124 rigidly but adjustably mounted

- on a shaft 125 (see also Fig. 1). The pads rotate so that their acting faces travel at a speed the same as that of the blanks, and the front pair is spaced from the rear pair 5 (peripherally) the same as the distance between the front and rear portions *e f* of the blank moving along below the pads. During each rotation of the pads they pass by and take glue from a roll 126 which is 10 driven at the same peripheral speed as the pads but in opposite direction. The roll takes a film of glue from a tank or trough 127 which may be suitably heated in a manner not necessary to describe or illustrate.
- 15 The roll is carried by a shaft 128 mounted in arms 129 pivotally supported on a rod 130 mounted in ears of the trough 127. In practice the arms rest on adjustable supports to enable the height of the roll to be 20 adjusted. Said arms, being pivoted, enable the roll to be swung up clear of the trough.

In alignment with the strips 121 and supported so as to constitute, practically, extensions thereof, are strips 131 which serve 25 to prevent the in-folded portions of the blanks from springing up while passing along for the further folding presently described.

When the glue is applied as described, 30 the blank is in the condition illustrated by Figure 17 and is travelling in the direction of the arrow adjacent that figure. The next operation is to fold the blank on the transverse crease line between sections *a b* so as 35 to bring flaps *g* onto the glued portions *e* (see Figure 18). At practically the same time, the flap *k* is folded onto the section *i*.

The blank is pushed along laterally toward the left in Figure 2 by the lugs of 40 the chains 112, said blank sliding on suitably supported plates 132 and travelling under a strip 136 supported by tie rods 137, 138. During this movement of the blank the flap *k* of the blank rides along upwardly and inwardly inclined folder rods 139, 140, supported by adjustably mounted brackets 141, said flap being thereby turned up and folded over to nearly the condition shown by Figure 18. At the same time the section *b*, 45 with its in-folded flaps *g*, rides along an inwardly and upwardly inclined folder rod 142 supported by adjustably mounted brackets 143, said rod 142 serving to turn the section *b* up and in toward the mid- 50 width of the blank. An inner bar 144 projecting from the end of a bracket 145 rigidly supported by the tie rod 137 guides the flaps *g* of section *b* to prevent them from unfolding as section *b* approaches final in- 55 turned position. The fold of section *b* is made complete by a pair of press rolls the upper one of which is indicated at 146 in Figure 2, said roll being carried by a shaft 147 mounted in arms 148 extending from the tie rod 138. It is to be understood that

below the shaft 147 and roll 146 are another shaft and a similar roll. This pair of rolls act upon the section *b* and its flaps *g* so that the latter are pressed down upon the portions *e* which are carrying glue, to permanently unite flaps *g* and portions *e*. 70

The shaft 147 also carries a pulley 149 for a belt 150 which runs also over another pulley 151 carried by a shaft 152, suitable belt tightener pulleys being employed as 75 indicated at 153. It is to be understood that a similar belt is below the belt 150 to cooperate therewith in carrying the blank through to the delivery end of the machine. Such two belts and their pulleys serve to 80 complete the fold of the flap *k* of the blank.

As the blank, now in the condition shown by Figure 18, is carried along by the belt 150 and its companion belt below it, the next and last folding operation occurs on the 85 crease line between sections *a* and *c*, the completion of which operation carries the glue-bearing portions *f* over onto the flaps *h* and causes them to be permanently united 90 (see Figure 19). This final or third fold on a transverse crease line is effected by several devices one of which is a twist belt 154 mounted at its delivery end on a pulley 155 carried by shaft 152, and at its other end on a pulley 156. Said pulley 156 is mounted 95 on an axle-pin carried by a bar 157 which is rotatably and longitudinally adjustable in a bearing 158 at the inner end of a bracket bar 159. This adjustable mounting of the pulley 156 provides for varying both the 100 twist and the tension of the belt 154. In practice we find it desirable to employ adjustable pulleys intermediate the pulleys 155, 156, to guide the acting stretch of the belt 154, but as such are well known in box 105 folding machines, and are not claimed herein, it is unnecessary to illustrate them.

Cooperating with the belt 154 to turn the section *a* and all the previously folded parts which are integral therewith, up and over to the condition shown by Figure 19, are two curved rods 160, 161. The rod 160 is adjustably carried by a clamp 162 the shank 163 of which is carried by a block 164 adjustably clamped on a bracket rod 115 165. The rod 161 has an integral shank or arm 166 adjustably mounted in a clamp block 167 carried by the inner end of a bracket rod 168. The blank, as it moves along, is partially supported by a lower belt a portion of which is indicated at 169 in Figure 2, said blank passing under a down-hold or guiding strip 170 hung below and supported by the bracket rod 168.

It is to be understood that the portion of 125 the twist belt which is on the pulley 156 is below the plane of the blank, and the acting stretch of the belt passes to a higher plane at the delivery end. Said acting stretch therefore acts upon the under side of the

portion *a* of the blank to turn said portion up. As this occurs, the portion *b* is pressed against the outer side of the rod 161 with sufficient force to keep said portion *b* from unfolding relatively to the portion *a*. This is desirable for the reason that the machine is so rapid in its operation (the blanks passing very fast) that the glue has not set sufficiently to be relied upon to hold the flaps *g* stuck to the portions *e*.

Under the folding influence of the belt 154, the advancing edge of the portion *a* and the parts integral therewith reaches and passes inside the rod 160 which then operates with the final twisted portion of the belt in completing the folding to the condition shown by Figure 19. In this condition the boxes are ready for storage or shipment to customers who then set them up for use, when required, as indicated by Figure 20.

Mechanism for driving the various parts of the machine in properly timed relationship may, obviously, vary from that illustrated in the drawings. The mechanism shown includes a shaft 196 adapted to be driven by a belt shiftable from one to the other of fast and loose pulleys 171, 172. At the end of shaft 196 is a bevel pinion 173 meshing with a bevel pinion 174 of a shaft 175 (Fig. 3). At the other end of shaft 175 is a gear 176 meshing with a gear 177 of shaft 28. A pinion 178 carried by a shaft 197 meshes with gear 179 of shaft 25. A chain 198 is mounted on sprockets carried by shafts 175, 197. The shaft 197 has sprockets on which the blank-forwarding chains 32 are mounted. The shaft 196 (Fig. 1) extends under shaft 125 and, through suitable gearing, drives the gear 198' of shaft 125. The shaft 125 has a gear 198' meshing with a gear 180 of the shaft of the glue roll 126. The shaft 196 has a bevel pinion 181 meshing with a bevel pinion 182 of a shaft 183 (Figs. 1 and 2) mounted in bearings at the side of the frame of the second section of the machine. The shaft 183 has bevel pinions 184, 185, meshing respectively with bevel pinions 186, 187, which are carried by shafts directly below the shafts 147, 152, which said lower shafts have gears meshing with gears 188, 189, of shafts 147, 152.

The chains 112 extend from the first section of the machine into the second section and, with their lugs 113 (Fig. 11), serve to push each partly folded blank (Fig. 17) from the table plates 111 until said blank is taken by the belt 150 and a companion belt below it acting on the folded portions *k* *i*, and belts 154, 169 acting on the portions *a* *c*. Said chains 112, at their ends shown in Figures 1 and 11 are carried by sprockets 190 mounted to rotate on pins 191

carried by arms 192 pivotally supported on a rod or shaft 193. Each arm 192 has a pin 194 connected to it and extending through the frame bar 20 and provided with nuts 195 by means of which the sprockets 190 can be independently adjusted to secure proper tension of the chains. The other ends of the chains (Fig. 2) are mounted on sprockets 199 carried by a shaft below shaft 147.

The shaft 196 (Fig. 1) has a bevel pinion 200 meshing with a bevel pinion 201 carried by one end of the roll shaft 109 which, at its other end (Fig. 11), has a gear 202 meshing with a pinion 203 of the shaft of the upper roll 106.

The operation of the various parts of the machine having been described further explanation of the operation of the entire machine will be unnecessary.

The method according to which the blanks are cut and then folded as described results not only in economy of material and rapidity of production but also in furnishing the boxes to the trade in collapsed condition and having no exposed flap portions liable to become interengaged with portions of other adjacent boxes. The collapsed boxes present only smooth continuous upper and under surfaces as will be readily understood from Figure 18, all wall portions being folded and confined between the bottom section *a* and the cover section *i*. Consequently the boxes can be readily piled up or stacked in neat relationship or can be removed singly from a pile or shelf, for use, without dislodging others below. The continuous smooth flat surface of the portions *c* *i* *k* enables a box to be slid relatively to the portion *a* of the next box without interengaging it in any such manner as to displace the latter.

Having now described our invention, what we claim is:—

1. The method of making wall boxes in collapsed condition adapted to be set up for use, consisting in cutting a sheet without waste of material to provide a plurality of blanks having reversely complementary edges, folding marginal portions of the blank in toward each other on parallel longitudinal lines, applying glue to some of the in-folded marginal portions, and then folding the blank on transverse lines to cause the glue-bearing in-folded portions to adhere to other in-folded marginal portions.

2. The method of making boxes from blanks which are cut and creased to provide a bottom section, front and rear wall sections and a cover section all of which are of uniform width, the bottom section having foldable marginal portions and the front and rear wall sections having foldable flaps said method consisting in first folding said

- 5 marginal portions and flaps inwardly onto the bottom and front and rear wall sections, then applying glue to predetermined areas of the in-folded marginal portions, and then 5 folding the blank on the lines between the bottom section and the front and rear wall sections.
- 10 3. The method of making boxes from blanks which are cut and creased to provide a bottom section, front and rear wall sections and a cover section, the bottom section having foldable marginal portions and the front and rear wall sections having foldable flaps, said method consisting in first 15 folding said marginal portions inwardly, then folding corners of the marginal portions outwardly, then folding said flaps inwardly, then applying glue to the said outwardly folded portions, and then folding 20 the blank on the lines between the bottom section and the front and rear wall sections.
- 25 4. In a machine of the character described, blank-carrying mechanism, and independently operative folders for successively acting upon different areas of two opposite marginal portions of the blanks.
- 30 5. In a machine of the character described, blank-carrying mechanism, oppositely mounted folders for folding marginal portions of a blank inwardly, and outwardly 35 operative folders for doubling said marginal portions.
- 35 6. The method of making wall boxes in collapsed condition adapted to be set up for use, consisting in forming blanks of sheet material with foldable marginal portions projecting from two opposite edges, folding 40 said marginal portions in toward the mid-width of the blanks, folding the blanks on transverse lines to superimpose some of the in-folded marginal portions at each side of 45 the blanks on other in-folded marginal portions at the same side of the blanks, and securing said contacting marginal portions together.
- 50 7. In a machine of the character described, blank-carrying mechanism, inwardly movable folders for acting upon marginal portions of a blank, and outwardly 55 operative folders for doubling said marginal portions.
- 55 8. In a machine of the character described, blank-carrying mechanism, inwardly and downwardly movable folders for acting upon marginal portions of a blank, and outwardly and downwardly 60 movable folders for turning parts of said marginal portions back.
- 60 9. A machine for folding box blanks having laterally projecting marginal portions, comprising blank - carrying mechanism, means for first completely folding said marginal portions, means for applying glue to predetermined areas of the folded marginal

65 portions, and means for folding the blank on lines at a right angle to the line of the first folding operation.

70 10. A machine for folding blanks having laterally projecting marginal portions, comprising two blank-carrying mechanisms at an angle to each other, means for folding said marginal portions while the blank is in that part of the machine having one of the blank-carrying mechanism, means for applying glue to predetermined areas of the folded 75 marginal portions while the blank is under the control of the other blank-carrying mechanism, and means for folding the body of the blank after the application of the glue.

80 11. A machine for folding wall-box blanks comprising two successively operating folding mechanisms at an angle to each other the first being constructed and arranged to fold the blanks on longitudinal lines and the second being constructed and arranged 85 to fold the blanks on transverse lines, and means for applying glue to wall portions of the box blanks after completion of the folding on longitudinal lines.

90 12. A machine for folding wall-box blanks comprising two successively operating folding mechanisms at an angle to each other the first being constructed and arranged to fold the blanks on longitudinal lines and the second being constructed and arranged to 95 fold the blanks on transverse lines, and a plurality of rotary glue applicers located in position to apply glue to predetermined portions of the longitudinally folded portions of the blanks while they are on their way to be 100 transversely folded.

105 13. A machine of the character described comprising a first portion having means for causing a blank to travel and means for completely folding marginal portions of it on longitudinal lines, and a second portion at an angle to the first portion, said second portion having means for causing the blank to travel and also having means for folding the blank 110 on transverse lines and laying some of the previously folded marginal portions of the blank on other marginal portions, the machine having means for applying glue to some of said marginal portions at a point intermediate the longitudinal and transverse 115 folding.

120 14. In a machine of the character described, a pair of travelling blank-forwarding lug carriers, means for supplying a blank to a position of rest in advance of and spaced from the lugs of said carriers, and folders movable to and from position to operate on marginal portions of the blank before said lugs reach its rear edge.

125 15. In a machine of the character described, a pair of travelling blank-forwarding lug carriers, means for supplying a blank to a position of rest in advance of and spaced

from the lugs of said carriers, means for turning marginal portions of the blank to upright positions while the blank is moving to said position of rest, and folders movable to and from position to operate on the upturned marginal portions before said lugs reach the rear edge of the blank.

16. In a machine of the character described, a pair of outside folders movable to and from position to operate on marginal portions of a blank to fold said portions inwardly, and a plurality of inside folders movable outwardly to re-fold or double over said marginal portions.

17. In a machine of the character described, means for supplying blanks singly and successively to a position of rest, a pair of outside folders movable to and from position to operate on marginal portions of each blank to fold said portions inwardly, and a plurality of inside folders movable outwardly to re-fold or double over said marginal portions.

18. In a machine of the character described, a pair of outside folders movable inwardly and downwardly to operate on marginal portions of a blank, and a plurality of outwardly and downwardly movable folders to re-fold or double over said marginal portions.

19. In a machine of the character described, a pair of outside folders movable inwardly and downwardly to operate on marginal portions of a blank, and a plurality of inside folders mounted to swing on vertical axes to re-fold or double over said marginal portions.

20. In a machine for making folded wall boxes, means for supplying blanks singly and successively to a position of rest, a pair of rock shafts having folding blades to operate on marginal portions of each blank, means for moving said rock shafts toward each other, and means for oscillating said shafts as they approach their inner positions to swing said folding blades down.

21. In a machine for making folded wall boxes, means for supplying blanks singly and successively to a position of rest, outside folders for turning marginal portions of each blank inwardly, a pair of co-axial shafts mounted above said position of rest, each of said shafts having folding wings extending forwardly and rearwardly, and means for oscillating said shafts in opposite directions to swing said folding wings outwardly.

22. In a machine for making folded wall boxes, means for supplying blanks singly and successively to a position of rest, tapering outside folders for turning marginal portions of each blank inwardly, and outwardly movable inside folders to double portions of said marginal portions back over the tapering edges of the outside folders.

23. In a machine for making folded wall

boxes, means for supplying blanks singly and successively to a position of rest, a pair of outside folders movable to and from position to operate on marginal portions of each blank to fold said portions inwardly, a plurality of inside folders to re-fold or double over said marginal portions, blank forwarding mechanism to remove the blank from its position of rest, and operating connections to effect outward movement of the outside folders before the blank forwarding mechanism operates to remove the blank from the said position of rest.

24. In a machine for making folded wall boxes, folders for folding marginal sections of a blank inwardly and for folding portions of said sections outwardly, means for pressing the blanks after they are so folded, forwarding means for transporting the blanks from the folders to the pressing means, and means for holding the said marginal sections in folded condition while they are being forwarded to said pressing means.

25. In a machine for making folded wall boxes, folders for folding marginal sections of a blank inwardly and for folding portions of said sections outwardly, rolls for pressing the blanks after they are so folded, forwarding means for transferring the blanks from the folders to the pressing rolls, and means for holding the said marginal sections in folded condition while they are being forwarded to the said rolls.

26. In a machine for making folded wall boxes, folders for folding marginal sections of a blank inwardly and for folding portions of said sections outwardly, means for pressing the blanks after they are so folded, forwarding means for transferring the blanks from the folders to the pressing means, means for holding the said marginal sections in folded condition while they are being forwarded to the pressing means, and folders for deflecting flaps of the blank into alignment with the said folded marginal sections.

27. A box folding machine having a pair of endless blank-forwarding lug carriers, means for folding blanks forwarded by the lugs of said carrier, and a pair of rolls for taking blanks from said carriers, means being provided for driving the rolls at a peripheral speed exceeding the speed of travel of the lug carriers to cause said rolls to pull the blanks away from the lugs and press the folded blanks.

28. A box folding machine having a pair of endless blank-forwarding lug carriers, means for folding blanks forwarded by the lugs of the carrier, and a pair of rolls for taking blanks from said carriers, said rolls being relatively mounted to exert yielding pressure on the blanks, means being provided for driving the rolls at a peripheral speed exceeding the speed of travel of the

- lug carriers to cause said rolls to pull the blanks away from the lugs and press the folded blanks.
29. A machine for making folded wall boxes, comprising two folding mechanisms at an angle to each other, a table intermediate said mechanisms, one of said mechanisms being constructed and arranged to completely fold a blank on longitudinal lines 10 and the other being constructed and arranged to complete the folding of the blank on transverse lines, a pair of rolls for delivering the longitudinally folded blank onto the table, means for frictionally arresting 15 the blank as soon as its rear edge leaves the nip of said rolls, and means for carrying the blank from the table through the mechanism for transversely folding it.
30. A machine for making folded wall boxes, comprising two folding mechanisms at an angle to each other, a table intermediate said mechanisms, one of said mechanisms being constructed and arranged to completely fold a blank on longitudinal lines 20 and the other being constructed and arranged to complete the folding of the blank on transverse lines, a pair of rolls for delivering the longitudinally folded blank onto the table, a movable frame above the table 25 for aiding in frictionally arresting the blank as soon as its rear edge leaves the nip of said rolls, and means for carrying the blank from the table through the mechanism for transversely folding it.
31. A machine for making folded wall boxes, comprising two sections at an angle to each other the first section having means for folding side wall portions of a blank and the second section having means for applying 30 glue in separate locations to the said folded wall portions and also having means for transversely folding the blank.
32. A machine for making folded wall boxes, comprising two sections at an angle to each other the first section having means for folding side wall portions of a blank and the second section having rotary glue pads to contact with predetermined areas of 40 said folded wall portions, the second section also having means for transversely folding the blank.
33. A machine for making folded wall boxes, comprising two sections at an angle to each other the first section having means for folding side wall portions of a blank to present upwardly facing triangular areas and the second section having rotary glue pads the operative faces of which are shaped 50 to correspond with the shape of said upwardly facing areas, the second section also having means for transversely folding the blank.
34. A machine for making folded wall boxes, comprising two sections, one section 55 having means for folding wall portions of a blank to prepare them for receiving glue, the other section having means for applying glue to predetermined areas of said wall portions and also having means for folding the blank to cause the glue bearing areas to adhere to other areas of the wall portions.
35. A machine for making folded wall boxes, comprising two sections, one section having means for folding wall portions of a blank to present two upwardly facing triangular areas at each side of the blank, the other section having two pairs of rotary glue pads shaped and spaced to apply glue to the said upwardly facing triangular areas and also having means for transversely folding the blank.
36. A machine for making folded wall boxes, comprising two sections one of which includes means for folding marginal portions of a blank on lines longitudinal of the 85 blank, the other section having means for folding the blank on transverse lines.
37. A machine for making folded wall boxes, comprising two sections one of which includes means for folding marginal portions of a blank on lines longitudinal of the 90 blank, the other section having means for first folding the blank on two transverse lines simultaneously and then folding on an intermediate transverse line.
38. A machine for making folded wall boxes, comprising a plurality of successively operating folding mechanisms, and carrying devices for causing the blanks to travel progressively through the machine, the first of 100 said mechanisms including devices for folding marginal portions of the blanks inwardly, the next including devices for folding the blanks on two transverse lines; and the next including devices for folding the 105 blanks on a third transverse line.
39. A machine for making folded wall boxes, comprising three successively operating folding mechanisms, carrying devices for causing the blanks to travel progressively 110 through the machine, the first of said mechanisms including devices for folding marginal portions of the blanks inwardly, the second including devices for folding the blanks on two transverse lines, and the third 115 including devices for folding the blanks on an intermediate transverse line, and guides for preventing those portions of the blanks which have been folded by the second mechanism from unfolding while on their way to the third mechanism.
40. A machine for making folded wall boxes, comprising a plurality of successively operating folding mechanisms, carrying devices for causing the blanks to travel progressively through the machine, the first of 120 said mechanisms including devices for folding marginal portions of the blanks inwardly, the next including devices for folding the blanks on two transverse lines, and

the next including devices for folding the blanks on a third transverse line, and means for applying glue to predetermined areas of the marginal portions of the blanks after those portions have been folded inwardly.

41. A machine for making folded wall boxes, comprising carrying mechanism for causing blanks to travel progressively through the machine, a plurality of folding mechanisms in different locations relatively to the carrying mechanism, and means intermediate said folding mechanisms for preventing unfolding of the previously folded portions of the blanks.

42. A machine for making folded wall boxes, comprising carrying mechanism for causing blanks to travel progressively through the machine, a plurality of folding mechanisms in different locations relatively to the carrying mechanism, means for applying glue to predetermined areas of the blanks, and means intermediate said folding

mechanisms for preventing unfolding of the previously folded portions of the blanks.

43. In a box folding machine, blank carrying mechanism, means for doubling a portion of a blank onto its body, mechanism including a twisted belt for folding that portion of the blank having the doubled portion, and a curved stationary member in position to prevent unfolding of the said doubled portion during the action of the twisted belt.

44. In a box folding machine, blank carrying mechanism, folding mechanism including a twisted belt, and a pair of curved rods adjacent to the belt to cooperate therewith in ensuring correct folding of the blanks, a space being provided between said rods for the passage of portions of the blanks between them.

In testimony whereof we have affixed our signatures.

LEON E. LA BOMBARD.
MELVIN H. SIDEBOOTHAM.
